TRESTLE CLAMP

Harold D. Strand, St. Paul, Minn.

Application December 6, 1945, Serial No. 633,223

7 Claims. (Cl. 304—5)

1

This invention relates to a trestle clamp and more particularly to a clamp for demountably clamping together the supporting legs of a trestle and the cross plank or beam or support connecting two such clamping means. This novel device is adapted to form a trestle such as is used by carpenters, masons, plasterers, etc. and is of the knock-down type wherein substantially a minimum number of relatively small parts of a complete trestle need be transferred from one job to another. It does not employ bolts, nuts, screws or nails and lends itself to inexpensive production and to simplicity in use.

It has been common practice to construct trestles wholly of wood either on the site of each particular job or to construct them and convey them from one job to another. The construction of trestles at the place of each particular job is time-consuming and expensive and the conveyance of pre-constructed trestles from one job to another is inconvenient and expensive.

An object of the invention is to provide a simple and efficient form of trestle clamp of the knock-down type.

Another object is to provide such a trestle clamp with a few sturdy parts which may be easily and conveniently transported from one job to another.

Embodying the above objects and others which may hereinafter appear, the invention consists in the novel construction, combination and arrangement of parts as will be more specifically described and illustrated in the accompanying drawing wherein is shown an embodiment of the invention, but it is to be understood that changes, variations and modifications may be resorted to within the scope of the invention as claimed.

In the drawings:

Figure 1 is a view in side elevation of a pair of novel clamps in assembled relation with supporting legs and a cross beam, the clamp on the right having an outside portion cut away to show the interior;

Figure 2 is a vertical section on the line 2—2 of Figure 1 and showing the parts in assembled clamping relation;

Figure 3 is a view similar to Figure 2 but showing the position of the parts before being moved to clamping position;

Figure 4 is a plan view of the left end of the trestle shown in Figure 1;

Figure 5 is a cross-section on the line 5—5 of Figure 2 and particularly showing the tops of the abutment members carried by the clamping elements;

Figure 6 is a cross-section on the line 6—6 of 55

Figure 2 and particularly showing the lower guide members and the lower clamping portions of the elements; and

Figure 7 is a view on the line 7—7 of Figure 1 showing the connection of the diagonal braces to the ledger or cross beam.

Referring to the drawings and particularly to Figure 1 thereof, there is shown an assembled trestle of the type used by carpenters, masons, plasterers, etc., to provide a platform elevated above the ground or floor level and by the use of which workmen may have ready access to areas normally beyond reach and for other well-known purposes. In the ordinary use of such trestles two of them are positioned in spaced relation to act as a supporting means for one or more flat boards spanning them and thus providing a temporary flooring. Of course, such a single trestle may be used as a supporting structure from which objects may be suspended such as a swing.

This trestle clamp is well adapted for use with the ordinary 2 x 4 lumber of which trestles are ordinarily constructed and of which lumber there is usually an adequate supply.

25 This novel clamp is preferably made in a substantially trapezoidal form with two side members and upper and lower connecting side members. Each of the outer members 8 and 9 is preferably formed of relatively rigid channeled material, such as iron, with the channels inwardly opposed. As shown in the drawings these two outer members are preferably disposed in upwardly converging relation. Each of the upper outer opposite sides of these outer members is connected by a cross bar 10 while the similar lower opposite sides are connected by a cross bar 11. These four cross bars are fixedly secured to the outer members as for example by welding or brazing.

40 Each one of the clamping elements 12 and 13 is formed of relatively rigid channeled material such as iron and the channels inwardly face although each clamping member (like the outer members) could well be formed of non-channelled rigid material. These clamping elements are united, as by welding, at the lower ends by a base 14. This base is desirably formed of a relatively resilient metal and the lower end of each clamping element is welded to its upper face. The base 45 extends outwardly beyond the clamping elements as shown in Figures 2 and 3 and each opposite end of the base 14 is provided with a downwardly curved clamping face 15. The advantage of the use of a relatively resilient material for the base 14 resides in the fact that it permits the upper

unconnected ends of the clamping elements to be spread apart to receive a ledger or trestle beam 16.

These two clamping elements have a guided movement relative to the trapezoidal structure. Extending across the top of the structure between the upper cross bars are two guide bars 17 as shown in Figure 4. Similar guide bars 18 are adjacent the lower end of the structure and extend between the lower cross bars 11. These upper and lower cross bars at their intermediate portions are provided with recesses 19 within which the clamping members are positioned for guided relative movement.

Somewhat above the middle portion of each clamping element and on the outer face of each thereof is welded or otherwise secured an angled bracket constituting an abutment 20. Each abutment as shown in Figures 2 and 3 is substantially L-shaped and is welded to the base at its angled portion so that the two sides of the L extend at an angle to the plane of the back of each clamping member.

Preferably a boss 21 is placed on the outer face of one of the clamping elements. This boss may be formed by a few drops of melted iron and its function is normally to prevent the downward descent of the relatively slideable clamping elements through the guide bar recesses 19. While the boss normally prevents accidental disassociation of the clamping bars and the structure, yet the clamping bars may be forced together at their upper ends sufficiently so that the boss 21 will pass through the lower guide bar recess. In normal use it is preferred to have the clamping elements remain with the structure.

This clamping structure also preferably includes a pair of brace rods 22. Each brace rod consists of a U-shaped rod pivotally mounted in a sleeve 23 welded to the exterior of one of the lower cross bars. Each of the two free ends of the brace rods has fastened thereto an open ended staple 24 with the sharpened points opposing each other. The brace rod 22 is adapted to be upwardly swung when the trestle beam is in position with one staple on one side of the beam and the other on the opposite side. Preferably a metallic plate 25 with two guide holes is mounted upon the U-shaped brace. When the plate 25 is in its lowered position, as shown in Figure 6, the outer ends of the brace may be easily parted to straddle the trestle beam as there shown. In assembly the plate 25 is manually outwardly moved to the position shown in Figures 1 and 4 so that the pointed ends of the staples 24 are firmly embedded in the side of the wooden beam 16 and there held.

The simplicity of assembly is well shown in Figures 2 and 3. As shown in Figure 3, the clamping elements 12 and 13 are in their lower positions. A ledger or common form of trestle beam 16 has been loosely placed between the upper ends of the two clamping elements while two supporting legs 26 of a common 2 x 4 lumber have been inserted within the outer members 8 and 9. These 2 x 4 legs may be of any convenient length to give the desired height to the assembled trestle. The upper ends of the wooden legs abut against the outwardly projecting faces of the angled abutments 20 while the clamping faces 15 are out of engagement with the inner faces of the legs.

One simple mode of clamping is to turn the associated parts (Figure 3) upside down and then grasp the legs and downwardly press them with the beam 16 upon the ground until the assembly binds and then forcibly pound or bang the assem-

bly against the beam 16 upon the ground. Such force causes the beam 16 to force the upper cross bars 10 and the connected outer members 8 and 9 upwardly (being inverted) so that the parts are forced to the position shown in Figure 2 when that figure is inverted. The wooden legs, as a result of the impact downwardly, force the two abutments 20 downwardly and thus cause the two clamping elements likewise to move relatively to the outer members so that the parts assume the clamped position disclosed when one inverts Figure 2 of the drawings.

Thereafter the assembled clamped parts are restored to the upright position as viewed in Figure 2 when restored to normal position wherein it is seen that the clamping faces 15 of the base 14 have forcibly clamped the supporting legs and the upper or outer ends of the channeled clamping elements 12-13 have been relatively upwardly and inwardly moved to clamp the trestle beam.

The clamps are adapted for use in pairs with a ledger or beam 16 extending between them. Obviously any weight borne by the beam 16 only clamps the parts more firmly together.

Additional fixation of the assembled trestle is provided by the brace rods 22 which are next placed in position as heretofore described. While the above mode of assembly seems to be the most convenient, one may also assemble the parts in the position shown in Figure 3 and then hammer or pound the beam 16 downwardly so that the outer members 8-9 are downwardly forced along the sides of the legs 26 which rest upon the ground or floor. Such relative movement causes the clamping faces 15 to engage and clamp the inner faces of the supporting legs and the result is the same as above described.

After use the clamped parts may easily be disassociated by upwardly pounding either cross bar 10 or 11 of the shorter members whereby the beam is released and removed from the clamping elements and thereafter upwardly pounding the lower cross bar 11 of the outer members whereby the outer members are upwardly moved relatively to the clamping elements from the position in Figure 2 to that of Figure 3 whereupon the two supporting legs are unclamped and may easily be removed.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. A trestle clamp adapted to secure together a pair of supporting legs and a transverse beam in clamped assembled relation, comprising a pair of spaced outer members, means rigidly connecting the outer members to each other to provide a hollow structure, a pair of relatively movable clamping elements positioned within the structure to permit insertion of one of said supporting legs at each side between an outer member and a clamping element, the elements being spaced apart at their upper ends to receive said transverse beam, clamping means carried adjacent the lower end of each element to engage an adjacent side of an inserted leg whereby, upon forced rel-

ative movement of the clamping elements and structure, the legs and beam are securely held in clamped relation.

2. A trestle clamp having two side members and upper and lower connecting members forming a hollow substantially trapezoidal structure, a pair of relatively movable clamping elements positioned within the structure so as to permit insertion of a supporting leg at each side between a side member and a clamping element, the elements being spaced apart at their upper ends to receive a trestle-forming instrumentality, clamping surfaces carried adjacent the lower end of each element to engage a side of an inserted leg whereby, upon relative movement of the elements and side members, the legs and instrumentality are securely held in clamped relation.

3. A trestle clamp comprising two outer members spaced apart, means rigidly securing together the upper and lower portions of the members, guides carried by said securing means, clamping elements slidably borne by the guides, a base resiliently connecting the lower portions of said clamping elements whereby the upper portions of the elements may be forced apart to receive and tensionably grip a trestle device, clamping means on each end of said base and adapted to engage and clamp a supporting leg inserted between each clamping means and an outer member whereby said parts may be assembled into clamping relation upon relative movement of the outer members and the clamping elements.

4. A trestle clamp comprising two outer members spaced apart, upper and lower cross-bars rigidly securing the upper and lower portions of the members together, guides carried by the upper and lower cross-bars, clamping elements slidably borne by the guides, a base resiliently connecting the lower end portions of said elements, the upper portions of said elements being spaced to receive a trestle beam, clamping means on each end of said base adapted to engage an adjacent face of an inserted supporting leg whereby upon forced relative movement of the clamping elements and the outer members the supporting legs and beam are securely clamped together.

5. A trestle clamp comprising two outer members disposed in opposed upwardly converging relation, each outer member being formed of rigid channeled material with the channels inwardly opposing, upper and lower cross bars at the upper and lower outer sides of the outer members rigidly securing them together to form a substantially trapezoidal structure, guide bars extending in spaced relation between the lower cross bars, a pair of spaced clamping elements extending upwardly between the inner faces of the guide bars and movable therebetween, the upper portions of the clamping elements being spaced to receive a transverse beam, a relatively resilient base fixedly secured to the lower portions of the clamping elements, clamping means on each end of said base adapted to engage an adjacent face of an inserted supporting leg whereby upon forced relative movement of the clamping elements and said structure, the supporting legs and beam are securely clamped together.

6. A trestle clamp adapted to secure together a

pair of supporting legs and a transverse beam in clamped assembled relation, comprising a pair of spaced outer members, means rigidly connecting together the outer members to provide a hollow structure, a pair of relatively movable clamping elements positioned within the structure to permit insertion of one of said supporting legs at each side between an outer member and a clamping element, the elements being spaced apart at their upper ends to receive said transverse beam, an abutment fixedly carried by each element and extending into the space between such element and the inner face of the opposed outer member so that the upper end of each inserted leg may terminally engage an abutment, clamping means adjacent the lower end of each element to engage an adjacent side of an inserted leg whereby, upon forced relative movement of clamping elements and structure, the legs and beam are securely held in clamped relation.

7. A trestle clamp comprising, two outer members disposed in upwardly converging opposed relation, each outer member being formed of relatively rigid channeled material with the channels inwardly opposing, upper cross bars at the upper outer sides of the outer members rigidly securing them together, lower cross bars at the lower outer sides of the outer members rigidly securing them together, guide bars extending between the upper cross bars in spaced relation, guide bars extending between the lower cross bars in spaced relation, the cross bars and the outer members forming a relatively rigid substantially trapezoidal structure, a pair of spaced clamping elements extending upwardly between the inner surfaces of the upper and lower guide bars and slidably therebetween, a relatively resilient base fixedly secured to the lower ends of the clamping elements, the base having a downwardly extending clamping face at each end, an abutment on the outer side of each clamping element, said structure being adapted to receive a supporting leg at each side between the inner face of each outer member and the clamping face on the clamping base with each upper end of each supporting leg positioned against one of said abutments, the space clamping elements normally extending above the top of the structure and adapted to receive therebetween a trestle support, whereby when the supporting legs and trestle support are initially assembled the outer members and clamping elements may be forcibly moved relatively to each other to cause the base clamping faces to clamp the legs against the inner faces of the outer members and the upper portions of the clamping elements clamp the trestle support.
